UNITED STATES PATENT OFFICE.

MALCOLM L. COSSITT, OF ALAMEDA, CALIFORNIA, ASSIGNOR TO MANIFOLD IMPRESSIONS CORPORATION, OF CARSON CITY, NEVADA, A CORPORATION OF NEVADA.

MANIFOLDING ATTACHMENT FOR TYPEWRITERS.

1,407,935.

Specification of Letters Patent. Patented Feb. 28, 1922.

Application filed June 13, 1921. Serial No. 477,065.

To all whom it may concern:

Be it known that I, MALCOLM L. COSSITT, a citizen of the United States, residing at Alameda, in the county of Alameda and 5 State of California, have invented certain new and useful Improvements in Manifolding Attachments for Typewriters, of which the following is a specification.

My invention relates to that class of attachments for typewriters and other typing machines, such, for example, as calculating machines and the like, in which a manifolding ribbon is so associated with the machine as to be readily moved into and out of functional position.

The object of my invention is to provide a manifolding attachment of this class, simple in construction, effective in operation, and which can be readily applied to the 20 machine without appreciable changes or alterations therein.

To this end my invention consists in the novel manifolding attachment which I shall now fully describe by reference to the accompanying drawings, in which—

Fig. 1 is an end view of my attachment on the line 1—1 of Fig. 3, showing it applied to the platen-carriage of a machine.

Fig. 2 is a similar view showing the attachment thrown back.

Fig. 3 is a front view, broken, of the attachment as applied to the platen carriage.

Fig. 4 is a top view, broken, of the same.

Fig. 5 is a perspective view of the selective push-finger.

Fig. 6 is a perspective view of the connection between the manifolding ribbon and the sliding carrying sleeve.

Fig. 7 is a view showing the functional relation of the main inking ribbon, the manifolding ribbons and the sheets of paper.

1 indicates a pair of standards each having a foot 1'. In each standard is pivotally fitted by a pin 2 a head member 3' from which extends an arcuate guide 3. In practice there are a plurality of these guides as seen in Figs. 1 and 2; lying one above the other in spaced relation. I have for illustration here shown three such guides.

Upon each guide is slidably fitted a sleeve 4 to which is detachably connected a clip 5 on the end of a section, strip or length of manifolding ribbon 6. See Fig. 6. Each

ribbon extends between and is carried by 55 the corresponding sleeves 4 upon corresponding guides 3 at each end, as seen in Figs. 3 and 4, so that by the movement of the sleeves each ribbon may be independently caused to travel in an arcuate path 60 forward and back.

In order to secure the operation in unison of the pairs of corresponding sleeves there is a lever 7 pivoted by its foot to an angular extension 7' of the head member 3' 65 of each set of guides 3. These levers extend upwardly past the outer edges of the guides 3, and they are connected to operate in unison by a rod 8, and said levers are provided with handles 9.

Carried by each lever is a push finger 10, having a shoulder 11 adapted to contact with the sleeves 4 from the back. Thus when either lever 7 is moved forwardly carrying with it the opposite lever 7, the push 75 fingers 10 engaging their respective sleeves 4 will carry said sleeves and the manifolding ribbon 6 which extends between them forwardly and downwardly in an arcuate path to their lower limit; and upon 80 being moved back will leave them down. The ribbon may then be moved up again by hand directly, but, if desired, it may be moved up by means of a pivoted spring latch 12 carried by the fingers; said latch 85 being normally held back by contact with the back of the finger but adapted by manual release to spring forward to carry its foot portion 13 in front of and in contact with the sleeve. Thus when the fingers 90 move up, the latches 12 will carry the sleeves and their ribbon back again to their upper limits.

Now, in order, when a plurality of manifolding ribbons are used, to invest the push 95 fingers with automatic ribbon-selective function, said fingers are pivotally carried by the levers by pins 10', and are controlled by springs 14 tending to press them down into successive contact with successive pairs 100 of sleeves 4. When all the sleeves 4 are back in their elevated rear position, the fingers 10 rest against the outermost pair of sleeves with their shoulders 11 lying upon and back of said sleeves. When the fingers move 105 forward they will carry with them this pair of sleeves and the ribbon they bear. When the fingers move back, leaving the

ribbon in its forward position, the springs 14 will press the fingers in so that their shoulders will drop in behind the sleeves 4 of the next pair, and this pair, with the 5 ribbon they bear, may then be moved forward; and so on with each ribbon. The ribbons, either singly, or as a group, may be moved back by throwing into action the spring latches 12 as heretofore described.

10 As the pivotal points of the levers 7 are here shown as being eccentric to the axis of the arcuate guides 3, provision is made for retaining the proper engagement of the push fingers with the sleeves, by giving 15 their pivot pins 10' a play back and forth in a slot 15 in the levers 7.

The application of my attachment to the platen-carriage of a typing machine may now be described. 16 is a part of the frame of 20 the platen carriage; 17 is the platen; 18 is the platen shaft; 19 is the paper guide apron; 20, in Fig. 4, is the main inking ribbon; and 21, in Fig. 7, are the sheets of paper. The standards 1 of my attachment 25 are fitted on the platen carriage beyond the ends of the platen, and the extensions 7' of the heads 3' are fitted under keepers 22 secured to the carriage and adapted to swing thereon to release said extension.

30 The arcuate guides 3 follow substantially the arc of the platen, as shown in Fig. 1. It will now be seen that by the movement 35 of the sleeves 4 the manifolding ribbons 6 may be carried in an arcuate path, from their rear position, forwardly and down to their functional position in the line of type-impact and back again.

As their path of movement is substantially or approximately concentric with the 40 curvature of the platen, due to the arcuate guides 3, the whole attachment may be applied in close relation to the platen, thereby securing compactness, even in the non-functional position of the ribbons, and also con- 45 ducing to simplicity of construction in that more or less complex provision need not be made for an eccentric or distorted path, to secure the proper or accurate functional po-

sition of said ribbons. When, however, it is necessary for any purpose, the whole attachment may be thrown upwardly and backwardly well out of the way, by turning it on its pivotal connection at 2, as shown in Fig. 2.

I claim:—

1. A manifolding attachment for typewriters and the like, comprising a pair of standards adapted to be mounted on the platen-carriage of the machine, one at each end of the platen; an arcuate guide carried by and extending forwardly from each standard; a carrying member slidably mounted on each guide; a manifolding ribbon carried by and between said members; and means for moving said members in unison to carry the ribbon in an arcuate path to and from a functional position in the line of type-impact, consisting of a lever pivotally associated with each standard; a connection between said levers; and means carried by the levers and acting on the carrying members to effect their movement.

2. A manifolding attachment for typewriters and the like, comprising a pair of standards adapted to be mounted on the platen-carriage of the machine, one at each end of the platen; an arcuate guide carried by and extending forwardly from each standard; a carrying member slidably mounted on each guide; a manifolding ribbon carried by and between said members; and means for moving said members in unison to carry the ribbon in an arcuate path to and from a functional position in the line of type-impact, consisting of a lever pivotally associated with each standard; a connection between said levers; a push finger carried by said levers adapted to engage said members to move them forward; and a latch carried by said fingers and engaging said members to move them back again.

In testimony whereof I have signed my name to this specification.

MALCOLM L. COSSITT.
